UNITED STATES PATENT OFFICE.

CHARLES HARDY, OF NEW YORK, N. Y., ASSIGNOR TO AMSCO PRODUCTS, INC., OF NEW YORK, N. Y., A CORPORATION OF NEW YORK.

FASTENING MEANS.

Application filed October 26, 1925. Serial No. 64,722.

This invention relates to improvements in fastening means or clips for instrumentalities such as fountain pens, pencils or the like.

5 The principal object of my present invention comprehends the provision of fastening means or clips for instrumentalities such as pens or pencils comprising a resilient clip or clamping portion attached to the 10 barrel of the pen or pencil by anchoring means constructed to inhibit longitudinal and lateral displacement of the clip on the barrel, while producing an effective resilient clamping function, the clip embodying a 15 construction having parts which may be manufactured and assembled with great facility and ease and with a minimum amount of labor.

A further object of the invention comprises the provision of a resilient fastening means or clip of the character referred to which may be made of a single piece of highly tempered sheet metal fashioned so as to be attachable to a pen or pencil barrel 25 with a single escutcheon pin, which latter may be made of relatively soft and bendable material, whereby a highly resilient clip may be made which is readily and securely attachable to the pen or pencil barrel. A 30 relative object of the invention resides in the provision of a fastening means or clip embodying a method of and means for anchoring the clip to the pen or pencil barrel designed to permit a large factor of error in 35 the accuracy of machining the parts, and to permit rapid assembly of the same in quantities, while producing an assembled clip which is strong and resilient in action.

Further objects of the invention include 40 the provision of a clip of the character referred to anchored to the pen or pencil barrel by means of a tongue integral with the clip and a single escutcheon pin securing the clip to the barrel, with means provided 45 active in opposite directions on the tongue and escutcheon pin for securely locking the clip on the barrel and for increasing the resilient action thereof.

To the accomplishment of the foregoing 50 and such further objects as will hereinafter appear, my invention consists in the elements and their relation one to the other, as hereinafter particularly described and sought to be defined in the claims; reference being had to the accompanying drawings which

show the preferred embodiment of the invention, and in which:

Fig. 1 is a side elevation partly broken away, showing by way of illustration a fountain pen cap and clip,

60 Fig. 2 is a section taken on line 2—2 of Fig. 1,

Fig. 2^a is a section taken on line 2^a—2^a of Fig. 2,

65 Fig. 3 is a modified form taken in a direction similar to Fig. 2, and

Fig. 4 is a section taken on line 4—4 of Fig. 3.

For purposes of illustrating my invention, I have shown my attaching clip as applied 70 to the cap of a fountain pen, but this is by way of example only, as my device has utility in combination with any instrument which it is desired to retain in position against accidental displacement.

75 The cap 10 is a hollow cylindrical member having a hollow portion or barrel 11, one end thereof 12 being open, the opposite end thereof 13 being closed, preferably as by means of a plug 14 securely held in position either frictionally or by screw engaging means 15. For purposes of attachment to portions of the garment of a user, and to prevent accidental displacement of the instrumentality, I provide an attaching clip 80 16 having an offset resilient portion 17 provided with a camming knob 18 at one end thereof and an anchoring portion 19 at the other end thereof. The anchoring portion 19 is preferably made form-fitting as where 85 the portion 10 is circular in cross-section, and has its terminal end 20 provided with an inwardly directed anchoring member 21 in the form of a tongue preferably disposed at right angles to the portion 19. There is 90 also provided intermediate the length of the anchoring portion 19 an escutcheon pin 22. To accommodate the body portion 10 for engagement with the anchoring portion of the clip 16, I provide for the escutcheon pin 95 22, hole or orifice 23 and for the anchoring member, the engaging hole or orifice 24. These holes 23 and 24 are spaced apart from each other so as to receive fairly snugly the pin 22 and the anchoring member 21. Preferably, however, the hole 24 is made somewhat enlarged and with tapering walls, thus affording a large factor of error in the 100 accuracy of machining the parts to accommodate those portions they are to receive.

105

110

For assembling the cap 10 and the clip 16, the escutcheon pin 22 previously attached to the clip 16 is inserted, so that the anchoring member 21 and the pin 22 simultaneously enter the openings 23 and 24 provided for each in the body member of the cap 10. Thereupon, the pin 22 is turned over or upset over the inner face of the barrel 11. This may be accomplished by means of a mandrel, or may be accomplished in a manner to be described hereinafter.

It will thus be observed that my clip as thus far described, serves efficiently as a fastening means, having suitable means in the form of the pin 22 for anchoring the clip longitudinally of the cap and means in the form of the inwardly turned tongue 21 for anchoring the clip laterally of the cap.

An important feature of the construction resides in that the clip member 16 may be made of highly spring tempered material whereas the escutcheon member 22 may be made of relatively soft, easily bendable material. This escutcheon member 22 may be positioned as by riveting, but preferably it is positioned by inserting a mandrel and turning over the protruding portion. This method of attachment has particular utility where the body member barrel 11 is made of plastic composition material.

In order to more efficiently coordinate the longitudinal anchoring means and the lateral anchoring means of the clip, I further combine therewith means for causing the terminal end 20 and the pin 22 to resiliently coact with each other by oppositely disposed engaging forces. This I accomplish by providing an abutment for the inwardly directed tongue 21 serving to force the tongue 21 outwardly. In my preferred embodiment, I accomplish this by inserting within the tubular portion a sleeve 25 which is frictionally or otherwise positioned and having a lower shoulder 26 which forms the abutment for the complementary member of the instrument, as for instance, the bent portion of the fountain pen. The sleeve 26 preferably has on its outer face a flattened portion 27 adapted to engage the inwardly protruding end of the tongue 21 at 28. Preferably, this flattened face 27 is diagonally disposed so that as it is positioned, it will serve to act as a wedge block against the tongue 21 gradually forcing it outwardly to an extent sufficient to take up any "play" at the other point of attachment of the escutcheon pin.

It will be observed in this connection, that the sleeve 25 may serve to act as the means for bending the escutcheon member into fastening engagement, the diagonally disposed flattened wall 27 also serving efficiently to bind the terminal edge of the escutcheon member 22 between the inner wall 11 and its outer face.

It will be further observed that the wedge

surface 27 of the inner sleeve 25 serves to dispose the forces between the tongue 21 and the escutcheon pin 22 in opposite directions so that the clip 16 is resiliently and securely locked on the tubular member or barrel 11. Moreover, as the direction of movement of the ball point 18 is opposite to that of the terminal end 20, it will be observed that the forces are applied in a manner serving most efficiently their intended purpose for effecting secure resilient attachment of the clip to the pocket of a garment.

In Fig. 3, I have illustrated a slightly modified form in which the clip has the escutcheon member countersunk to receive the head 22'. The lateral anchoring hole in this form as shown in 24' is preferably elongated and has slightly angularly disposed side walls 24', allowing a variable factor of error in the accuracy of machining the parts.

It will also be observed that I have illustrated my escutcheon member in the form of a pin, that this member may be a flattened pin and the holes passing through the body member to the clip 16 be made correspondingly.

It will also be observed that though I have described the abutment for the inwardly directed tongue 21 as being in the form of a separately positioned sleeve, this abutment may be integral with the body 11.

It will thus be observed that I have provided a fastening clip having unusual simplicity of construction and involving a method of attachment to a pen or pencil cap requiring a minimum amount of operation and facility of manipulation in securing the same.

While I have shown my invention in the preferred form, it will be apparent that many changes and modifications may be made in the structure disclosed without departing from the spirit of the invention, defined in the following claims.

I claim:

1. The combination with a tubular member of the character described, of a clip therefor made of highly tempered resilient material, means for anchoring the clip on the tubular member against longitudinal and lateral displacement thereon comprising a single escutcheon pin made of easily bendable metal having its inner end bent into engagement with the inner wall of the tubular member for securing the clip to the tubular member and a tongue formed by making a single bend in the top end of the clip inwardly and at right angles to the body of the clip, the said tongue being received by an orifice in the tubular member.

2. The combination with a tubular member of the character described, of a clip therefor, means for anchoring the clip on the tubular member against longitudinal and

lateral displacement thereon comprising a single escutcheon pin securing the clip to the tubular member and a tongue formed by making a single bend in the top end of the clip inwardly and at right angles to the body of the clip, the said tongue being received by an orifice in the tubular member, and means disposed within said tubular member active on said escutcheon pin and tongue in opposite directions to hold said clip resiliently on the tubular member, the said means forming an abutment for the tongue to outwardly urge the same against the resilience of said clip and pin.

3. The combination with a tubular member of the character described, a resilient clip therefor, means for attaching the clip to the member comprising spaced anchoring means adapted to pass through openings in said member, one of said anchoring means including an escutcheon pin passing through openings in said clip and member and turned over within the same, the other of said anchoring means comprising an inwardly turned tongue integral with the clip, projecting through said tubular member, and an internal sleeve forming an abutment for said tongue to outwardly urge the same against the resilience of said clip and pin.

4. The combination with a tubular member of the character described, a resilient clip therefor, means for attaching the clip to the member comprising spaced anchoring means adapted to pass through openings in said member, one of said anchoring means including a bendable escutcheon pin passing

through openings in said clip and member and turned over within the latter, the other of said anchoring means comprising an inwardly turned tongue projecting through 40 said tubular member, and a sleeve arranged within said tubular member forming an abutment for said tongue to outwardly urge the same against the resilience of said clip and pin and forming a wedge for said turned 45 over portion of said pin to wedge the same against the walls of the tubular member.

5. The combination with a tubular member of the character described, a resilient clip therefor, means for attaching the clip to the 50 member comprising spaced anchoring means adapted to pass through openings in said member, one of said anchoring means including an escutcheon pin passing through an opening in said clip and member and turned 55 over within the same, the other of said anchoring means comprising an inwardly turned tongue integral with the clip, projecting through said tubular member, and an internal sleeve forming an abutment for said 60 tongue to outwardly urge the same against the resilience of said clip and pin, the opening receiving said tongue having tapered walls accommodating variations in the distance or spacing between said anchoring 65 means without permitting any lateral play or movement of the clip parts.

Signed at New York city, in the county of New York and State of New York this 22nd day of October, A. D. 1925.

CHARLES HARDY.
